UNITED STATES PATENT OFFICE.

RICHARD WEBB BURNETT, OF MONTREAL, QUEBEC, CANADA.

DUMP-CAR.

1,096,351.

Specification of Letters Patent.

Patented May 12, 1914.

Application filed September 11, 1912. Serial No. 719,828.

To all whom it may concern:

Be it known that I, RICHARD WEBB BURNETT, a citizen of the United States of America, residing at the city of Montreal, Province of Quebec, Dominion of Canada, have invented certain new and useful Improvements in Dump-Cars; and I do hereby declare that the following is a full, clear, and exact description thereof.

10 My invention relates particularly to dump cars of the type disclosed in my United States Patent application Serial No. 655,253, filed Oct. 17th, 1911, and which resulted in Patent No. 1,081,430.

15 My invention consists in a hinge for hopper doors adapted to close to positions in approximately vertical planes, and comprises a pair of hinge members each of which has a series of hinged knuckles,—the 20 knuckles of both hinge members interdigitating and being kept in alinement by a pin-tile extending from end to end of the hinge, and mounted in bearings in hopper-end walls,—the hinge members being so relatively arranged that when the door is closed 25 the edges proper of such hinge members contiguous to the knuckles will come into contact, as shown in Fig. 1, thus preventing leakage of the finest mesh lading there- 30 through.

For full comprehension, however, of my invention reference must be had to the accompanying drawings forming a part of this specification in which similar reference 35 characters indicate the same parts, and wherein:

Figure 1 is a vertical sectional view of a dump car hopper taken on a line extending transversely relatively to the car; Fig. 2 40 illustrates a dump car door in elevation and provided with my invention; Fig. 3 is a detail sectional view taken on line A A Fig. 1 of one of the flanged ends of the door and the hopper in which it engages; Fig. 4 is a 45 detail perspective view of a portion of the hopper floor member and one end wall; Fig. 5 is a detail perspective view of the clamping device; Fig. 6 is a detail elevation of the means for locking the door clamping 50 means; and Fig. 7 is a detail sectional view of the means for mounting the hinge bar.

The hopper floor is indicated at *b* and the hopper end-plates at *c*, the floor extending from the center sill *d* of the car to within close proximity of the vertical plane of the side sill *e* of the car thus placing the

discharge opening approximately perpendicularly. The center sill *d* and side sill *e* of the car constitute hopper sills. The dump door *f* is hinged to the floor member 60 and its ends are flanged as at *g* and engage pockets *g'* in the front edges of the hopper ends while the free side edge of the door engages a flange *s* upon the side sill, and it is clamped in its shut position, after having 65 been manually closed, by a rock-shaft *i* carrying a series of dogs *J*. This type of door forms an extension of the floor of the hopper and throws the lading a considerable distance laterally, which is an advantage 70 in that it is thrown clear of the rails. With doors of this type and applied in the manner described to hoppers through which granular commodities are discharged, while the free edges are effectively closed against 75 leakage by the clamping appliance described, the hinged edge has been heretofore a source of trouble owing to leakage due to wear, imperfect fitting, and, in some cases, inherent weakness unless constructed 80 from extra heavy materials. In order to overcome these defects the hinge consists of a pair of plates forming the door and floor member respectively and one edge of each plate is formed with hinge knuckles 85 consisting of spaced tongues *m* and *n*, respectively, struck from sheet metal and curved to tubular form or cast in that form, the knuckles of one plate being adapted to interdigitate with the knuckles of the other 90 plate while they collectively form when alined in effect a practically continuous tubular hinge, the parts of which are maintained in alinement and the hinge itself and through it the door are supported by a 95 hinge bar *o* mounted in a socket *p* secured to the end plates of the hopper, and rigidly secured to the knuckles of the door by rivets *u*.

A hinge of the form described effectively 100 prevents leakage between the door and hopper floor member, and is strong and durable and of simple construction.

I do not herein claim the hinge construction as the same forms the subject-matter of 105 a separate application to be subsequently filed.

What I claim is as follows:—

In a hopper for dump cars, end plates, 110 hopper sills at the opposite sides of the top thereof, an inclined floor member extending from one of said sills to within close proxim-

ity of the vertical plane of the other of said
sills, a door for closing the opening inclosed
by the end plates, the floor, and the last
mentioned sill; and a hinge joining the door
5 and the floor member, and consisting of a
series of spaced hinged knuckles rigidly
secured to the door and floor member re-
spectively, the knuckles of both members
interdigitating; a pintle extending through
10 the interdigitating hinge knuckles, and

sockets upon the end walls of the hopper
receiving and supporting the pintle.

In testimony whereof I have signed my
name to this specification in the presence of
two witnesses.

RICHARD WEBB BURNETT.
